UNITED STATES PATENT OFFICE.

EDWARD H. SUMMERS, OF WAPELLA, ILLINOIS.

REVERSIBLE LATCH.

No. 927,189.

Specification of Letters Patent.

Patented July 6, 1909.

Application filed March 11, 1909. Serial No. 482,802.

To all whom it may concern:

Be it known that I, EDWARD H. SUMMERS, of Wapella, Illinois, a citizen of the United States, residing at Wapella, in the county of 5 Dewitt and State of Illinois, have invented certain new and useful Improvements in Reversible Latches, of which the following is a specification.

My invention relates to a combination reversible latch, composed of various parts, 10 and for use on single or double swinging or sliding doors or gates.

The object of my invention is to provide a reversible automatic latch, that may be attached on either side of swinging or sliding doors or gates, and especially adapted to those swinging on hinges one disposed above the other, permitting independent movement of the upper and lower sections.

With these objects in view, in describing 20 my invention in detail, reference will be had to the accompanying drawings which form a part of this specification wherein like characters denote corresponding parts in the several views, in which,—

Figure 1, is a front view with the latch in position as it appears attached to double doors when closed, one section above the other. Fig. 2, is a front view of the shield 30 plate and main body of the latch, adjusted in such manner as to permit the opening of the upper door section without interfering with the lower. Fig. 3, is a sectional view looking perpendicularly from above. Fig. 4, is a 35 view of the flange on the main plate, with dotted lines showing the keeper embracing the latch. Fig. 5, shows the interior latch lift, extending through the door or gate frame, in position to engage the latch on the 40 door or gate.

My invention consists of a friction or shield plate, 1, attachable by means of a screw through suitable opening 2, to the lower edge of the upper section of a swinging 45 door or gate, perpendicularly disposed above the lower, and directly above the main body of the latch on the lower section of the door or gate, the bottom of the upper meeting the top of the lower provided with square or beveled edges, the beveled as shown by dotted line 3, preferred, as in this manner the door sections can be operated as single sections, the keeper retaining them in position, but this is not essential to the operation of the 50 latch.

The hasp 4, attachable to the door or gate

by screws through suitable openings, is provided with lateral flanges, 5—5, projecting outwardly at right angles to the plate, in these flanges are perpendicular open slots, 60 6—6, arranged to accommodate the latch, 7, as it extends horizontally through a like slot in the base plate, as herein shown. The flanges have beveled upper edges, permitting the latch to slide up over these edges, 8, and 65 drop into the slots by its own weight. They are also provided with openings, 9, near the bottom, for purposes hereinafter stated.

10 is the base plate, provided with suitable openings for screws to attach to the door or 70 gate, and flanges at the ends, 11—11, projecting outwardly at right angles to the plate, in which are perpendicular slots, 12—12, to receive the latch in conjunction with the slots 5—5 in the hasp 4. The upper edges 75 of these flanges are beveled, 13, permitting the latch to ride up over them and drop into the slots, by its own weight. They are provided with openings near the bottom, 14, corresponding with like openings 9, in the 80 flanges 5—5, through which a fastening device may be inserted if desired. Approximately in the center lengthwise, and near the upper side of the plate 8, is a pivot 15, engaging the three members, the latch 7, 85 keeper 20 and the handle 16, in the manner detailed. The latch 7, pivoted at one end at 15, operates horizontally in the slots of the main plate 10 and extends beyond, engaging the slots 6—6 in hasp 4. 90

16 is a curved gravity handle, attached at one end to the base plate 10 by pivot 15, and in its handle as it extends along the base plate, is an opening 17, in proximity to the pivot, and on the interior of its curving portion is provided a gravity weight, 19, of sufficient dimensions to cause the handle to drop by its own weight, thereby causing the latch to operate automatically. 95

The keeper 20, is a movable plate approximately V shape in outline, attached at its smaller end to the pivot 15, with a curved extremity as shown by dotted line 21, projecting beyond the pivot, where it is provided with a lug 22, extending outwardly at right 100 angles to the body of the keeper, which lug extends through and operates in opening 17 of the handle, substantially as shown. This keeper is provided with a flange, 23, on its upper or larger end, extending outwardly at 105 right angles with its main portion, in which is provided an inclosed slot extending along 110

the flange, as shown, 24—24, through which the latch 7 extends sufficiently to engage the slots in the main plate 10 and the hasp 4, when in a horizontal position.

5 25 is an interior latch lift, pivoted at 26, to the door or gate frame, extending outwardly, through the frame, as shown by dotted line 28, and so arranged as to raise the latch on the floor or gate on the outside. The end of 10 the latch 7, is tapered at its end 7', and when the latch is applied to sliding doors or gates, the rounded portion will permit it to slide up into the slot 24 until the neck of the latch reaches the slot, when the latch engages the 15 bottom of the slot and drops into place.

From the foregoing description of my device, the working in detail of the various parts shows that the handle 16, the keeper 20, and the latch 7 are pivoted at a single 20 point on the base plate 10; that the handle being provided with a gravity weight, 19, on the interior of its curved portion, and an opening 17, in which operates lug 22 of the keeper, by manipulation of the handle the 25 keeper is raised or lowered as desired by the operator, and by this action, the latch operating in slot 24—24, raises or lowers, and on releasing the handle it drops by its own 30 weight, causing the keeper to rise and engage the upper section of the door or gate at plate 1, holding the door or gate in a closed position; the keeper is lowered by raising the handle, the opening in the handle, 17, engaging lug 22 on the keeper causing it to 35 move up or down as the handle is raised or lowered by the operator. The latch 7, extending through the slot 24—24 in the keeper, operates in conjunction with it, moving up or down as the keeper moves up or down, and 40 this is controlled in its movements by the handle 16 by the opening 17 engaging the lug 22 on the keeper. The keeper assumes an elevated position as the operator releases the handle, and when the door is closed, 45 holds it thus in position. If the upper section, or the double door is to be closed, a quick movement or shove and the upper section striking the flanges on the keeper, forces it down, thereby raising the handle, which 50 falling by its own weight, raises the keeper and holds the door closed, and the latch rides

up over the flanges on the base plate and the hasp, drops into the slots of these members, holding the door closed.

The foregoing description shows that the 55 latch can be used on the right or left side of the door or gate, working in all particulars in either position as here described.

Having described my invention, what I 60 claim and desire to secure by Letters Patent is:—

1. In a reversible latch of the class described, a base plate having flanges extending outwardly at right angles at its ends with beveled edges and perpendicular slots, to engage the latch as it drops into a horizontal position; a handle provided with a gravity weight and having an opening in proximity to one end; a keeper, approximately V shaped, with a lug on the extreme point extending outwardly at right angles to the main body, and a flange on the upper portion extending outwardly at right angles to the main body which is provided with an inclosed slot extending along the flange; a horizontally disposed latch extending through the slot in the keeper sufficiently to engage the slots in the base plate and hasp, and provided with tapering ends and shoulders forming an engaging portion, said handle, keeper and latch all pivoted approximately on the center of the base plate, a hasp with lateral flanges extending outwardly at right angles to the main body, with perpendicular slots in the upper portion, and with upper beveled edges and openings in the lower portion, substantially as described. 75

2. In a reversible latch of the class described, the combination of a movable keeper, a horizontally disposed latch and a gravity weight handle, all pivoted approximately on the center of a base plate; an interior latch lift operating on a pivot, and extending outwardly through the frame and so arranged as to raise the latch on the outside of the door 95 or gate, substantially as set forth.

In testimony whereof I affix my signature in presence of two witnesses.

EDWARD H. SUMMERS.
